PRECISION TILE SETTER

Stanley F. Paspy, Zanesville, Ohio, assignor to Ferro Corporation, Cleveland, Ohio, a corporation of Ohio

Filed Jan. 17, 1962, Ser. No. 166,757
11 Claims. (Cl. 25—153)

This invention relates to ceramic ware setters and has more particular reference to an improved setter for firing tabular ware such as tile and the like whereby warpage in said tabular ware is reduced to a minimum.

Warpage of flat tile bodies has always been a problem in the tile industry and the steps taken previously to reduce such warpage have met with little practical success for one reason or another.

Variations in body and glaze compositions, firing cycles and setter design have all failed to solve the problem of warpage encountered in today's fast one-fire operations, during which bisque and glost firing is combined.

The warpage difficulty has been minimized to a certain extent by specially designed setters wherein each tile is fully supported over its entire surface by a replaceable or fixed flat refractory slab. However, this method has the disadvantages of lowering fuel efficiency by introducing an excessive amount of dead mass into the firing operation by virtue of the great weight and bulk of such tile setter, and furthermore does not completely eliminate the warpage problem inasmuch as the heavy supporting slab for each individual tile has a tendency to warp during repeated firings, thereby tending to induce a corresponding warpage in the tile it supports. Thus, an attempt to overcome one problem (warpage) introduced another (inefficiency) because of the added mass of the slab type setter.

Through the design, some years ago, of a tile setter having generally vertical side walls with shelves projecting from said side walls just enough to support the tile adjacent two edges thereof, one problem (fuel inefficiency) was reduced to a certain extent by eliminating a substantial amount of setter weight introduced into the firing cycle.

Nevertheless, it was still found that "point" or "edge" support of tile in this manner resulted in an undesirable degree of warpage which was attributed to the fact that the tile was not supported over its entire surface, hence tended to sag and warp under its own weight during the firing operation.

However, I have surprisingly found that if two opposed corresponding and complementary tile supporting shelves are machined to very fine tolerances, with respect to a theoretical reference plane encompassing the machined tile supporting surfaces of the two shelves, significant warpage of tile fired while supported thereon is all but eliminated.

That is, we have found that if a tile is only partially supported over only a fraction of its surface, it nevertheless has sufficient strength to retain its flat shape if the points at which it is supported lie substantially in a plane.

Thus, a tile setter of the general improved type described provides both light weight and a supporting means for tile which tends to minimize warpage thereof during firing to a degree heretofore not possible.

It is, therefore, a principal object of this invention to provide a refractory tile setter having tile supporting means which vary from a plane, encompassing said means, within very close tolerances.

2

It is also an object of this invention to provide a light-weight tile setter for firing ceramic tile with a minimum of warpage therein.

It is a further object of this invention to provide means for supporting, during firing, a tabular ceramic body over only a fraction of its total surface, any point on the contacting surface of said means varying by less than 1.00% of the maximum dimension of the unsupported span of the tabular ceramic body to be fired, said variation determined with respect to a plane generally parallel to the plane of a tile supported on said means, and substantially encompassing the ceramic body supporting surfaces of said means.

In the attached drawings,

FIG. 1 is a perspective view of a preferred embodiment of our improved tile setter.

FIG. 2 is a side elevation view of said tile setter.

FIG. 3 is an enlarged side elevation section of two opposed shelves, shown in FIG. 2, with the slight inward and upward slope of said shelves exaggerated for clarity of description in the following disclosure.

Tile setters of the general type depicted in FIG. 1 have been achieved by any number of conventional forming techniques known in the ceramic industry, most popular of which has been slip casting.

As is well known, by the very nature of the forming methods and materials used in the refractory industry as well as the extremely high temperatures involved in firing articles of this type, it is practically impossible to achieve a fine degree of dimensional accuracy. Furthermore, since the consensus has always been that warpage in tile when fired in a setter of the general design of that depicted in FIG. 1, has been the result of factors other than minor variations in the tile supporting means, it is little wonder then that no one had previously conceived the thought of attempting to achieve unwarped ware through precise fabrication of the supporting means utilized by a tile setter of the general type shown in FIG. 1. Therefore, while my invention is relatively simple in its essentials, it should be borne in mind that the basic cause of tile warpage has never been previously proven to be the tile supporting means in this general type setter; the classic method of attacking the problem of warpage until my novel development lying in either "beefing up" existing tile setters by providing individual setter support plates for each tile, or by attempting endless variations in body and glaze compositions.

Referring now more specifically to the drawings, a tile setter constructed according to the present invention, manufactured by slip casting (although any conventional manufacturing method will suffice), embodies an open sided box-like structure having a top member 1, a bottom support member 2, and opposed vertical upright members 3 connected to said top and bottom members.

Vertical upright members 3 are provided with a plurality of tile support means 4 adapted to receive and support a ceramic tile 5 in the manner illustrated in FIGS. 1 and 2.

Referring now to FIG. 3, a preferred embodiment of our invention is achieved by machining with any suitable conventional abrasive means, such as a suitably mounted grinding wheel as I used, the tips of tile support means 4 over approximately the areas indicated by D and D' respectively to produce precision tile support surfaces 6 which are coincident with the plane P-P' within a tolerance of ± 0.015 inch; that is, any point

on surfaces 6 within the areas D and D' will not vary more than 0.015 inch above or below plane P-P' which includes therewithin surfaces 6. In my preferred structure the distance between two opposed upright members 3 is approximately four and one half inches, and the shortest distance (span) between two opposed support means 4 is approximately two inches, indicated by d in FIG. 3. It is therefore apparent that the variation limits of surfaces 6 from reference plane P-P' may be readily defined in terms of variation from such reference plane, P-P', expressed as a percentage variation of the span d, thus making my novel improvement applicable to any setter, regardless of span between tile support means.

Thus, in my preferred embodiment, the permissible variation of 0.015 inch may be equated to percentage of span, applicable to setters of any size, as follows:

$$\frac{0.015 \text{ inch variation} (V)}{2 \text{ inches span} (d)} \times 100 = 0.75\%$$

or

$$\text{Variation } (v) = 0.75\% d$$

I have found in successive trials, of varying degrees of tolerance, that any variation (v) less than 1.00% is permissible and provides the required degree of accuracy between opposed support means to reduce tile warpage, during firing, to an acceptable level. The percentage variation of 0.75% affords optimum results. Although less than 0.75% variation promotes even flatter tile, the improvement, in degree of flatness, or reduce warpage, is not sufficiently pronounced, in view of existing quality standards, to justify the added labor and expense of precision grinding to a variation less than 0.75%. However, it is to be understood that my invention obviously covers any variation less than 1%.

As is well known in the art, the shelves of my preferred embodiment may be replaced with suitable pins projecting inwardly from sidewalls 3, which provide a multiplicity of relatively sharp points for supporting flat ware, or my projecting shelves may be replaced with suitable slots in upright member 3 adaptable to receive and support a flat ceramic body during firing thereof, such as a tile, through supporting contact with only a fraction of a flat surface of said flat ceramic body. Too, the shelves of my preferred embodiment may obviously be formed to present knife edge ridges to the underside of a tile, which would provide "line" support for flat ceramic bodies during firing as opposed to "point" support from pins, or "area" support from a shelf surface.

The essence of my invention lies in an improvement for tile setters which consists of two or more generally opposed ceramic ware supporting means, all ceramic ware contacting points, edges or surfaces of said means lying substantially in a plane within the critical limits of variation from said plane as hereinbefore described.

Having thus described my invention in the foregoing specification in the form of a preferred embodiment thereof, but in no way intending to be restricted to the precise form thereof as disclosed, my invention is set forth in the following claims, to be accorded the broadest construction to which they are entitled by law.

I claim:

1. In a refractory ceramic ware setter having a generally horizontally disposed base, at least two generally opposed vertical upright members spaced apart from each other, in contact with and supported by said base, said upright members each carrying ceramic ware supporting means corresponding to and complementing generally opposed ceramic ware supporting means carried by an opposed upright member, the improvement in combination therewith of two opposed, corresponding, complementary ware supporting means, having ceramic ware supporting surfaces, characterized by a precision relationship between said means such that any given point on said ware supporting surfaces of either of said ware

supporting means varies from a reference plane described by any other three points taken on the ware supporting surfaces of said two means, at least one each of said three points occurring respectively on the ware supporting surface of each of said means, by less than one percent of the shortest distance between said two opposed ware supporting means.

2. The setter of claim 1 wherein said ware supporting surfaces are substantially unidimensional ceramic ware supporting edges.

3. The setter of claim 1 wherein each said ware supporting means consists in a multiplicity of points, and any given point of said means carried by either said upright member varies from a reference plane described by any other three points, at least one each of said other three points occurring respectively on each said opposed upright member, by less than one percent of the shortest distance between said two opposed ware supporting means.

20 4. The setter of claim 1 wherein said means are shelves.

5. The setter of claim 1 wherein said means are slots in said upright members.

6. The setter of claim 1 wherein said variation is 0.75 percent or less.

25 7. The setter of claim 1 wherein said variation is less than 0.5 percent.

8. In the method of manufacture of a refractory ceramic ware setter having a generally horizontally disposed base, at least two generally opposed vertical upright members spaced apart from each other, in contact with and supported by said base, said upright members each carrying ceramic ware supporting means corresponding to and complementing generally opposed ceramic ware supporting means carried by an opposed upright member, the manufacturing improvement step comprising forming a pair of said complementing generally opposed ceramic ware supporting means to provide them respectively with ceramic ware supporting surfaces having a precision relationship between same characterized by any given point on said ware supporting surfaces of either of said ware supporting means, varying from a reference plane, described by any other three points taken on the ware supporting surfaces of said two means, at least one each of said three points occurring respectively on the ware supporting surface of each of said means, by less than 1% of the shortest distance between said two opposed ware supporting means.

9. The method of claim 8 wherein said complementary ware supporting surfaces are formed to their precision relationship by honing.

50 10. In the method of manufacture of a refractory ceramic ware setter having a generally horizontally disposed base, at least two generally opposed vertical upright members spaced apart from each other, in contact with and supported by said base, said upright members each carrying ceramic ware supporting means corresponding to and complementing generally opposed ceramic ware supporting means carried by an opposed upright member, the manufacturing improvement step comprising forming a pair of said complementing generally opposed ceramic ware supporting means to provide them respectively with unidimensional ceramic ware supporting edges having a precision relationship between same characterized by any given point on said unidimensional ceramic ware supporting edges of either of said ware supporting means, varying from a reference plane, described by any other three points taken on the unidimensional ceramic ware supporting edges of said two means, at least one each of said three points occurring respectively on the unidimensional ceramic ware supporting edges of each of said means, by less than 1% of the shortest distance between said two opposed ware supporting means.

11. In the method of claim 8 wherein said ware supporting means consist in a multiplicity of points, the improvement of adjusting said points by honing to a relation-

ship characterized by any given point of said means carried by either said upright member varying from a reference plane described by any other three points, at least one each of said other three points occurring, respectively, on each said opposed upright member by less than 1% of the shortest distance between said two opposed ware supporting means.
